Patented May 22, 1917.

UNITED STATES PATENT OFFICE.

DOMINICK A. PASSARELLI, OF DANBURY, CONNECTICUT.

CHROMATIC-BASS GUITAR.

1,226,991.

Specification of Letters Patent.

Patented May 22, 1917.

Application filed August 4, 1915. Serial No. 43,577.

To all whom it may concern:

Be it known that I, DOMINICK A. PASSARELLI, a citizen of the United States, residing at Danbury, county of Fairfield, State 5 of Connecticut, have invented an Improvement in Chromatic-Bass Guitars, of which the following is a specification.

This invention has for its object to provide a guitar having a complete chromatic 10 bass scale without requiring an open string for each tone, and which will enable the player to play a harmony with a perfect bass in any key and in any position, with a minimum number of strings.

15 A further object of the invention is to provide a guitar of the type having supplemental bass strings with mechanical means operated by the left thumb for stopping the supplemental bass strings at will to raise the 20 pitch of a picked string or to stop the vibration of the supplemental strings.

A further object of the invention is to provide a guitar having a body cut away upon its outer side (when in position for 25 use) and the neck and supplemental neck placed obliquely to the center line of the body in the direction toward the player, so as to enable the player to play in the higher positions with greater ease.

30 With these and other objects in view I have devised the novel chromatic bass guitar which I will now describe, referring to the accompanying drawing forming a part of this specification and using reference characters to indicate the several parts.

Figure 1 is a perspective view of a guitar embodying my novel invention and indicating the note names of the ordinary and the supplemental strings;

40 Fig. 2 a section on an enlarged scale on the line 2-2 in Fig. 1; looking in the direction of the arrows;

Fig. 3 a section on the line 3-3 in Fig. 2, looking in the direction of the arrows;

45 Fig. 4 a section on the line 4-4 in Fig. 2, looking in the direction of the arrows;

Fig. 5 a detail view partly in elevation and partly in section illustrating a modification in which the stop bar is made adjustable, and

Fig. 6 is a view illustrating another modification in which the stop bar is dispensed with and the supplemental bass strings are stopped by other means.

10 denotes the body of a guitar, 11 the neck, 12 the frets, 13 the head and 14 the strings, which are the ordinary bass, E, A, D, and treble G, B and F. The head is enlarged and a supplemental neck 15 extends from the body to the head, lying substantially parallel with the neck 11 but separated therefrom so that the left thumb of the player is received freely between the necks. The body is cut away upon its outer side (when in position for use) as at 39, and the 15 neck and supplemental neck are placed obliquely to the center line of the body in the direction toward the player. This oblique position of the necks in connection with the cutting away of the body enables the player 20 to stop the strings in the higher positions much more conveniently than heretofore.

16 denotes the supplemental bass strings which are C, D, F, G, B-flat and C. These supplemental strings lie substantially parallel with strings 14 and are connected to the body by pins 17 and to the head by keys 18, in like manner with strings 14. The supplemental bass strings pass over a single fret 19 and over a notched bar 20 upon the 25 head near the supplemental neck. Between fret 19 and the notched bar is a stop bar 21 shown as carried by rods 22 which are adapted to slide vertically (as seen in Fig. 2) in the head. When the stop bar is pressed 30 down firmly upon the supplemental strings, its action is to raise the pitch a half-tone. For example, a C string, when stopped, will be raised to C-sharp. When the stop bar is pressed down lightly, its action is to stop 35 the vibration of picked strings. The lower ends of rods 22 are connected by a cross piece 23 having ears 24 between which one arm of a bell-crank lever 25 is pivoted. This lever is fulcrumed on a pin 26 extending 40 across a housing 27 which incloses the lever and is seated in a recess in the supplemental neck. 28 denotes a link which is pivoted to the other arm of the bell-crank lever, extends laterally through the supplemental neck and

45 50 55 60 65 70 75 80 85 90 95 100

is pivoted to an operating bar 29 which is partly socketed in neck 11 but projects from the socket into convenient position to be manipulated by the left thumb of the player. 5 This bar extends substantially from the head to the body and is carried by arms 30 pivoted to brackets 31 upon the neck. Springs 32 socketed in the neck, bear against the inner edge of the operating bar and act 10 to force it outward into operative position, and also act, by means of the link, bell crank lever and connections, to hold the stop bar in the raised position, as in Fig. 2. It is of course obvious that the supplemental strings 15 must be of different sizes. In order to insure that the smallest of these strings will be effectually stopped by the stop bar, I provide a pad of rubber, felt or other suitable material, indicated by 33, in the under side 20 of the stop bar. This pad has the additional function of preventing a metallic clang when the strings are released by the stop bar.

In Fig. 5, I have illustrated a form of stop bar which is made adjustable so that it can be tilted slightly to compensate for differences in the sizes of the strings. In this form, rods 22 carry a cross bar 34, and stop bar 21 is connected thereto by means of double-headed screws 35 which turn freely in the stop bar and have threaded engagement with the cross bar. The stop bar is locked at any required adjustment by means of set screws 36 which engage the cross bar and the 30 ends of which bear against the stop bar.

In the form illustrated in Fig. 7, fret 19 and the stop bar are dispensed with, and the stopping is effected by means of pins 37 carried by levers 38 pivoted to the head and 40 actuated by a link and operating bar as before.

The operation is as follows: The supplemental strings are picked by the thumb of the right hand and the operating bar is 45 manipulated by the thumb of the left hand, lying between the necks, to stop a picked supplemental string and raise its pitch a half-tone, or to stop the vibration of picked strings.

Having thus described my invention I 50 claim:—

1. In a guitar, the combination, with the usual fretted neck and the strings carried thereby, of supplemental strings and means 55 for carrying the same, means for stopping said supplemental strings, means located contiguous to said neck and manually operable at substantially any point throughout the length thereof for actuating said stopping means, and means for yieldingly retaining said stopping means in normally inoperative position and said actuating means in position to be operated.

2. In a guitar, the combination, with the usual fretted neck and the strings carried thereby, of supplemental strings and means 65 for carrying the same, means for stopping said supplemental strings, a bar longitudinally socketed in said neck and being laterally movable in its socket, and connecting means between said stopping means and said bar to operate the former.

3. In a guitar, the combination, with the usual fretted neck and the strings carried thereby, of supplemental strings and means 75 for carrying the same, means for stopping said supplemental strings, a bar longitudinally socketed in said neck and being laterally movable in its socket, connecting means between said stopping means and said bar to operate the former, and means for yieldingly 80 retaining said stopping means in normally inoperative position and said bar in position to be operated.

4. In a guitar, the combination, with the usual fretted neck and the strings carried 85 thereby, of a supplemental neck carrying supplemental strings, a fret on said supplemental neck, a stop-bar associated with said fret, means for operating said stop-bar, and means located contiguous to said first-mentioned neck for actuating said operating means.

5. In a guitar, the combination, with the usual fretted neck and the strings carried thereby, of a supplemental neck carrying 95 supplemental strings, a fret on said supplemental neck, a stop-bar associated with said fret, means for operating said stop-bar, and means located contiguous to said first-mentioned neck, and manually operable from 100 substantially any point throughout the length thereof for actuating said operating means.

6. A guitar comprising supplemental bass strings, a stop-bar therefor, vertically sliding rods having a cross-bar at their upper ends, adjustable connections by which the stop-bar is secured to the cross-bar, a cross-piece connecting the lower ends of the rods, an operating bar and connections intermediate said bar and the cross-piece for actuating the stop bar.

7. A guitar having supplemental bass strings, a stop-bar therefor, an operating bar substantially paralleling the usual fretted neck of the guitar, a link and intermediate connections between the operating bar and the stop-bar, and springs acting on the operating bar to retain said bar in position to be operated and the stop-bar out of operative position.

8. A guitar comprising supplemental bass strings, a stop-bar therefor, rods by which said bar is carried, a cross-piece connecting said rods, a link, a bell-crank-lever, one arm 125

of which is pivoted to the cross-piece and the other to the link, and a spring-controlled operating bar to which the link is pivoted.

9. A guitar comprising supplemental bass 5 strings, a stop-bar therefor, rods by which said bar is carried, a cross-piece connecting said rods, a link, a bell-crank lever, one arm of which is pivoted to the cross-piece and

the other to the link, an operating bar to which the link is pivoted, swinging arms by 10 which the operating bar is carried and springs acting on the operating bar for the purpose set forth.

In testimony whereof I affix my signature.

DOMINICK A. PASSARELLI.
